No. 835,746.

PATENTED NOV. 13, 1906.

H. F. BROWNE.

LAST.

APPLICATION FILED NOV. 29, 1905.

UNITED STATES PATENT OFFICE.

HENRY FRANKLIN BROWNE, OF SWAMPSCOTT, MASSACHUSETTS,
ASSIGNOR TO NAIL-LESS CUSHION HEEL-SEAT COMPANY, OF
LYNN, MASSACHUSETTS, A CORPORATION OF MASSACHUSETTS

LAST.

No. 835,746.

Specification of Letters Patent.

Patented Nov. 13, 1906

Application filed November 29, 1905. Serial No. 289,562.

To all whom it may concern:

Be it known that I, HENRY FRANKLIN BROWNE, of Swampscott, in the county of Essex and State of Massachusetts, have invented certain new and useful Improvements in Lasts, of which the following is a specification.

This invention relates to a last for making a shoe having a cushion-pocket in the heel portion, the bottom of said pocket being lower than the highest portion of the shank of the sole, so that a rubber cushion can be supported by the bottom of the pocket with its upper surface substantially flush with the highest portion of the shank, the portion of the innersole between the highest portion of the shank and the bottom of said pocket forming the forward end or wall of the pocket and preventing forward displacement of the cushion.

The invention has for its object, first, to provide a last adapted for use in forming a shoe having the above-mentioned cushion-pocket, and, secondly, to provide a last adapted for use in connection with an innersole, the heel portion of which has two parts or layers—viz., a bottom layer, which is adapted to form the bottom and forward end of said pocket, and a top layer, adapted to cover the cushion inserted in said pocket, the said top layer being interposed in the completed shoe between the cushion and the heel of the wearer's foot.

The invention consists in the improvements which I will now proceed to describe and claim.

Of the accompanying drawings, forming a part of this specification, Figure 1 represents a side view of a last embodying my invention. Fig. 2 represents a sectional view of the heel portion of the bottom of a shoe constructed by the aid of my improved last.

The same reference characters indicate the same parts in all the figures.

In the drawings, 2 represents a last the bottom surface of which is offset at the heel portion to form faces 3 and 4. The face 4 is inclined upwardly from the face 3 toward the shank-forming portion of the last, the two faces being adapted to form on an innersole the bottom 6 and front wall 7 of a pocket which is adapted to hold an elastic rubber cushion 8, the under side of said cushion resting

on the pocket-bottom 6, while the front end of the cushion rests on the front wall 7 of the pocket and is prevented by said wall from moving forward. The heel portion of the innersole is provided with a bottom layer, which includes the pocket-bottom 6 and front wall 7, and with a top layer 9, which in the completed shoe rests on the top surface of the cushion 8 and covers the latter, the top layer 9 being interposed between the cushion and the heel of the wearer's foot.

To enable the top layer 9 to be formed as an integral part of the innersole or to be attached thereto prior to the incorporation of the innersole in the shoe, I provide the last with means for holding the top layer 9 above the bottom face 3 of the heel portion of the shoe during all stages of the shoemaking operation which require the presence of the last in the shoe. The said means preferably include an opening 10, extending transversely across the bottom of the shank portion of the last, said opening permitting the top layer 9 to be deflected upwardly into a pocket 12 in the body of the last, as shown in Fig. 1, and held out of contact with the bottom layer until the construction of the shoe has reached a point which requires the removal of the last. The shoe after the removal of the last has an innersole with a divided heel portion, the bottom layer of which forms the bottom 3 and front wall 4 of the cushion-pocket, while the top layer forms a cover for the cushion inserted in said pocket, as shown in Fig. 2.

The top and bottom layers of the heel portion of the inner sole may be formed by splitting the said heel portion, the said layers being integral parts of the innersole, or the top layer may be made in a separate piece cemented, stitched, or otherwise attached to the innersole before the latter is incorporated into the shoe.

The last is preferably provided with metal bottom pieces 14 and 15, one covering the fore part and the other the heel part of the bottom of the last.

In Fig. 2, 16 represents the outer sole, which may be attached in any suitable way.

I claim—

1. A last having means for holding a transverse portion of an innersole above the bottom face of a portion of the last.

2. A last having means for holding the heel portion of an innersole above the bottom face of the heel portion of the last.
3. A last having a transverse opening in its bottom face extending from side to side of the last for the reception of a portion of an innersole.
4. A last having in its body portion a pocket located above the bottom face of the last, said pocket having a mouth extending across the bottom face of the last, between the heel and toe portions.

5. A last having the bottom face of its heel portion offset to form on an innersole the bottom and forward end wall of a heel-receiving pocket, and provided above said bottom face with means for holding a portion of the innersole above the said offset bottom face.

In testimony whereof I have affixed my signature in presence of two witnesses.

HENRY FRANKLIN BROWNE.

Witnesses:
